UNITED STATES PATENT OFFICE.

JOHN GRICE STATTER, OF BIRMINGHAM, ENGLAND, ASSIGNOR TO
WILLIAM MAXWELL SCOTT, OF PHILADELPHIA, PENNSYLVANIA.

TIME-ELEMENT DEVICE.

No. 830,537.

Specification of Letters Patent.

Patented Sept. 11, 1906.

Application filed July 31, 1905. Serial No. 272,066.

To all whom it may concern:

Be it known that I, JOHN GRICE STATTER, a subject of the King of Great Britain and Ireland, residing at Cornwall Buildings, Newhall street, Birmingham, in the county of Warwick, England, have invented new and useful Improvements in Time-Element Devices, of which the following is a specification.

10 My invention relates to time-element devices applicable to electric-circuit breakers and other apparatus, and has for its object to prevent an apparatus or part from being actuated by a force immediately upon the 15 application of that force, but to delay the actuation until the force has been applied for a period of time.

My invention is particularly, though not exclusively, applicable in the case of automatic circuit-breakers which are set to open a circuit when predetermined electrical conditions occur or exist in a circuit; and I shall describe my invention with reference to such a circuit-breaker.

25 Circuit-breakers are for the most part intended to interrupt a circuit to prevent the apparatus—such as motors, lamps, or other translating devices—in that circuit from being damaged by effects due to any abnormal 30 electrical condition in that circuit, and very commonly they are arranged to break the circuit when the current value in that circuit reaches or exceeds a given value. While an excessively-great current does damage to the 35 apparatus if allowed to persist, such current does not as a rule damage the apparatus in circuit if it is of only very short duration. It is therefore desirable in order to save needless resettings of the circuit-breaker by hand 40 that the circuit-breaker should only be tripped when the excess current has been passing for a period of time. To attain this end, various arrangements of dash-pots have been employed; but they are not satisfactory for 45 the reason that what a dash-pot does is not to postpone or delay the point of time at which an apparatus shall commence to act but to determine the rate at which it acts. It is therefore only in a secondary sense that a 50 dash-pot can be said to delay the point of time at which an operation commences.

My invention consists, therefore, in a device which for purposes of distinction I may term a "start-delaying" device, inasmuch as

it is the point of time of starting the operation (in the present case the opening of the circuit) and not the mere completing or other stage-reaching of the operation which is delayed.

More particularly my invention resides in a start-delaying device comprising a sucker, associated with the tripping mechanism of a circuit-breaker or with any other controlling mechanism.

For an illustration of several of the forms my invention may take reference is to be had to the accompanying drawings, in which—

Figure 1 is a vertical sectional view of a solenoid-tripping mechanism with the time-element device associated therewith. Fig. 2 is an enlarged view showing the movable sucker-disk and attached parts, partly in section. Fig. 3 is a vertical sectional view of a modified form of sucker-disk having channels therein. Fig. 4 is a plan view of the sucker-disk shown in Fig. 3. Fig. 5 is a fragmentary view, partly in vertical section, showing the arrangement of Fig. 1 modified by the application of a spring. Fig. 6 is a vertical view, partly in section, of a modified form of sucker involving the use of a flexible dome-diaphragm.

Referring to Fig. 1, the solenoid-winding 1 has the magnetizable core 2, which is adapted to be drawn up into the winding 1 by a magnetic action in the well-known manner. A casing 3 surrounds the solenoid and supports by its top wall a stationary core-piece 2', within which is mounted for vertical movement the pin 2^a, having the head 2^b. When the core 2 is drawn upwardly, it strikes the under side of the pin 2^a, causing the head 2^b to strike the latch or the latch mechanism of a circuit-breaker in the well-known manner. In the lower wall of the casing 3 and directly under the solenoid 1 is a circular opening threaded to receive the tube 4, of brass or non-magnetic material. The tube 4 instead of being screw-threaded for a length merely sufficient to prevent it from being securely held in the casing 3 is threaded throughout the whole of its length. A hollow cylinder 5 is threaded at its top opening to receive the tube 4. The inside of the bottom wall 6 is suitably surfaced and covered to a slight depth at least with liquid—such as oil, glycerin, or other suitable material. Obviously the relative positions of the tube 4 and the

cylinder 5 are easily adjustable. The solenoid core 2 extends downwardly into the tube 4 and has an axial hole 7 drilled therein and screw-threaded to receive the screw-threaded rod 8, of non-magnetic material. The length of the rod 8 below the core 2 is adjustable by screwing it into or out of the hole 7, and its position is maintained by means of the lock-nut 9. At the lower end of the rod 8 is a ball 10 member 10, forming one part of a ball-and-socket joint, the socket of which is formed by a cap 11, which screws onto a boss or projection 12 on the sucker disk or plate 13, as will be readily understood from Fig. 2. The lower face of the disk 13 is approximately truly plane as is also the upper face of the wall 6 of the cylinder 5 with which it makes contact. The weight of the solenoid-core 2 is sufficient to press the disk firmly upon the bottom wall 6.

The oil, glycerin, or other suitable material within the cylinder 5 is displaced by the disk 13 and the bottom wall 6.

The two surfaces or faces adhere together and are not easily separated by a sudden pull. The pull is, in fact, completely resisted and if continuing for a period of time is completely yielded to. This is entirely different behavior from the case of a dash-pot where the pull or force is yielded to from the very beginning, although retarded throughout its duration. It will be seen then that the disk 13 and wall 6 act precisely on the principle of a "sucker," as employed in the well-known child's toy of that name, or in a well-known form of railway reading-lamp where such a device is used for attaching the lamp to the car-window. As the tube 4 and cylinder 5 are easily adjustable with relation to each other it is possible to adjust the solenoid 2 to any desired position with respect to the winding 1, so that the core 2 would except for the time-element device immediately operate on the passage of any predetermined excess current to strike the pin 2^a and trip the circuit-breaker. This adjustment is made by rotating the cylinder 5, upon the tube 4, so as to raise or lower the core 2. The cylinder 5 has a pin or stud 14 projecting laterally from it, which pin or stud is engaged within a slot 15' in the spring 15, secured to the casing 3 at 16. The accidental or undesired rotation of the cylinder 5 under shock or vibration or for any other cause is thus obviated.

Instead of depending solely upon the weight of the core 2 to cause the disk 13 to displace the liquid in the cylinder 5 a spring 17, as shown in Fig. 5, may intervene between the top of the disk 13 and the bottom wall 4' of the tube 4.

In some cases the face of the disk 13 instead of being plane, as before described, may have depressions therein. Such depressions may comprise concentric channels 18, as shown in Figs. 3 and 4, or in some cases the

sucker may be constructed as shown in Fig. 6, where the ring-shaped sucker-plate 19 cooperates with the plate or wall 6. The flexible diaphragm 20, of leather, rubber, sheet metal, or other suitable material, is secured at its outer edge around its entire circumference to the ring 19 and has a small opening at its center to permit the passage of the rod 21, which carries at its lower end an enlargement or the valve 22. The rod 21 extends also through the hub 23, in which converge the arms 24, secured upon the ring 19. A valve-seat 25 is formed in the lower side of the hub 23, and onto this seat is forced the diaphragm 20 by the valve 22 when the rod 21 is drawn upwardly by the initial movement of the solenoid-core or the intervening mechanism. When the diaphragm is held against the seat 25 by the valve 22, an air-tight joint is made. Not until this position is reached is the start-delaying effect produced. Further continuance of pull upon the rod 21 will in time detach the sucker from the plate 6.

The operation of the start-delaying device is as follows: Having adjusted the cylinder 5 to the desired current value, the circuit-breaker is not tripped so long as the current is less than that value or exceeds that value for very short periods of time only. When the current does exceed the predetermined value, however, the magnetic force acting on the core 2 to draw it upwardly is transmitted through the ball-and-socket joint to the disk 13. Since the force persists or continues, the disk 13, because of its sucker-like action, eventually suddenly leaves the plate 6, and the core 2 rises un retarded throughout its entire movement and strikes the pin 2^a to trip the circuit-breaker. If, however, the excess current does not persist for such length of time, the parts remain in the position shown. If, however, a very heavy excess current occurs, the force acting upon the core 2 will be sufficient to suddenly and practically instantaneously pull the disk 13 away from the plate 6, so that the circuit-breaker will be tripped immediately upon the occurrence of the great excess of current. It thus appears that the start-delaying device is a device differentiating between forces of different magnitudes to yield to moderate forces only after a certain interval of time, but to yield practically instantly to very great forces. It is seen that the parts do not move at all during the excess current until the disk 13 leaves the plate 6, and then the parts move through their entire path without any retardation. In the case of a dash-pot the movement starts as soon as the excess current exists before the movement is retarded. There is a further disadvantage with a dash-pot in that as the core 2 rises the force acting on it increases, so that the parts move faster and faster. With the start-delaying device, however, there is practically no movement of parts until the

force has existed for a period of time sufficient to pull the disk from the plate 6. Furthermore, with this start-delaying device there is no backlash, a disadvantage common to dash-pot time-element devices. As an example of the mode of operation of this start-delaying device I may cite the results obtained with a circuit-breaker of a capacity of and adjusted for five hundred amperes. 5 When the current value was five hundred and twenty-five amperes in the circuit, the circuit-breaker did not open at all. With a current of six hundred amperes the circuit-breaker was opened in about sixty seconds. 10 With a current of seven hundred and fifty amperes it was opened in ten seconds. With nine hundred amperes it was opened in five seconds, and with two thousand amperes it was opened instantly. These measurements 15 were taken roughly; but they are sufficient to illustrate the law of the device.

What I claim is—

1. In controlling mechanism, the combination with a movable element, of a start-delaying device comprising a sucker.
2. In controlling mechanism, the combination with a movable element, of a start-delaying device comprising juxtaposed surfaces, and liquid adhering to said surfaces.
3. In tripping mechanism, the combination with an electroresponsive device, of a sucker associated with a movable element of said device.
4. In tripping mechanism, the combination with an electroresponsive device, of means associated with a movable element of said device operating to prevent initial movement of said movable element and thereafter to allow unretarded movement thereof.
5. In tripping mechanism, a movable tripping member, and a sucker associated therewith, whereby said member is initially retarded and after starting moves without retardation.
6. In controlling mechanism, the combination with a movable member, of a sucker for delaying the start of said member.
7. In controlling mechanism, the combination of a magnetizing-winding, a member adapted to be moved by force produced by said magnetizing-winding, and a sucker associated with said member.
8. In controlling mechanism, the combination of a solenoid-winding, a core co-operating therewith, and a sucker associated with said core.
9. In controlling mechanism, the combination with a movable member, of a movable element of a sucker connected therewith, a relatively stationary sucker element, and means for adjusting the sucker with respect to said movable member.
10. In tripping mechanism, the combination with a solenoid and its core, of a relatively stationary surfaced member adapted

to adhere thereto, and a co-operating surfaced member connected to the solenoid-core.

11. In tripping mechanism, the combination with a movable member, of a start-delaying device comprising relatively fixed and movable elements surfaced and fitting closely together.

12. In tripping mechanism, the combination with a movable member, of a start-delaying device comprising relatively fixed and movable elements surfaced and fitting together over considerable area.

13. In tripping mechanism, the combination with a movable tripping member, of a sucker, the movable element of said sucker being connected to said tripping member, and means for adjusting said movable sucker element with respect to said tripping member.

14. In tripping mechanism, the combination with a tripping member, of relatively fixed and movable sucker elements, a movable sucker element being connected to said movable member through an universal joint.

15. In tripping mechanism, the combination with a movable member, of relatively fixed and movable sucker elements, a movable sucker element connected to said movable member, and means for permitting said sucker elements to adjust themselves to each other.

16. The combination with a tripping mechanism of a circuit-breaker, of a sucker associated with the movable tripping member.

17. The combination with a tripping mechanism of a circuit-breaker, of means associated with the movable tripping member for delaying the start thereof.

18. The combination with the tripping mechanism of a circuit-breaker, of means associated with the movable tripping member for preventing the start thereof until after an interval of time and thereafter permitting the start and subsequent unretarded movement thereof.

19. In circuit-breaker tripping mechanism, the combination with a movable member, of a time-element device comprising a sucker.

20. The combination with the tripping mechanism of a circuit-breaker, of means associated with the tripping member for delaying the start thereof during the continuance of a predetermined electrical condition and yielding instantly upon the occurrence of a different electrical condition.

21. The combination with the tripping mechanism of a circuit-breaker, of means associated with the tripping member for delaying the start thereof during the existence of an abnormal current-flow and instantly yielding upon the occurrence of still greater current-flow.

22. In tripping mechanism, the combination with a tripping member, of means differ-

- entiating between forces of different magnitudes applied thereto to delay the start of said tripping member upon the application of a moderate force and to yield instantly to substantially greater force.
23. In controlling mechanism, the combination with a movable member, of a single device differentiating between forces of different magnitudes to delay the start of said member during the application of a moderate force thereto and to yield instantly under a substantially greater force.
24. In controlling mechanism, the combination with a movable member, of a time-element device consisting of a single means differentiating between forces of different magnitudes to retard said movable member during the application of a moderate force and to instantaneously release said member upon the occurrence of a substantially greater force.
25. In controlling mechanism, a movable member, a sucker element connected therewith, a stationary sucker element comprising a cup, and a film of liquid in said cup.
26. In controlling mechanism, a support, a movable member, a sucker element connected to said member, and a coöperating sucker element adjustable with respect to said support.
27. In controlling mechanism, a support, a movable member, a sucker element connected with said movable member, a coöperating sucker element comprising a cup, means for adjusting said cup with respect to said supporting member, and means for locking said cup in adjusted position.
28. In controlling mechanism, the combination with a movable member, of a start-delaying device comprising juxtaposed surfaces, and material adhering to said surfaces to oppose their separation.
29. In controlling mechanism, the combination with a movable member, of a start-delaying device comprising juxtaposed surfaces, and a thin layer of material between said surfaces and adhering thereto.
30. In controlling mechanism, the combination with a movable member, of a start-delaying device comprising juxtaposed surfaces adapted to adhere to each other.
31. In electrical controlling mechanism, the combination with a movable member, of relatively fixed and movable sucker elements, a movable sucker element being connected to said movable member by a ball-and-socket joint.
32. In electrical controlling mechanism, the combination with a movable member, of a relatively movable sucker element, and an universal joint between said sucker element and movable member.
33. In controlling mechanism, the combination with a movable member, of a start-delaying device comprising a sucker, an element of said sucker having a plurality of depressions in its active surface.

In witness whereof I have signed my name to this specification in the presence of two subscribing witnesses.

JOHN GRICE STATTER.
